UNITED STATES PATENT OFFICE.

WILLIAM M. BOENNING, OF MANITOWOC, WISCONSIN.

ADJUSTABLE GAGE MECHANISM.

1,125,261.

Specification of Letters Patent. Patented Jan. 19, 1915.

Application filed May 4, 1914. Serial No. 836,330.

To all whom it may concern:

Be it known that I, WILLIAM M. BOENNING, a citizen of the United States, and resident of Manitowoc, in the county of Manitowoc and State of Wisconsin, have invented certain new and useful Improvements in Adjustable Gage Mechanism; and I do hereby declare that the following is a full, clear, and exact description thereof.

10 The primary object of my invention is to provide a simple, effective and accurate adjustable gage mechanism adapted to co-act with a step by step movable carriage.

The invention is particularly designed as 15 an attachment to a button-hole stitching machine of any type and, when so applied, it serves as a gage whereby the distance between the first and last buttonhole of a series is divided into a predetermined number of 20 equal parts corresponding to the number of buttonholes required and, with this in view, the attachment is adapted to feed the goods to be operated upon step by step to an alined point under the needle of the machine.

25 The construction and arrangement of the gage is such that a series of link-connected stops are simultaneously spread apart or contracted equal distances with relation to each other and locked in their selected po-

30 sitions to conform to the spaces between the buttonholes to be worked upon a garment. These stops control the step by step feed of a slideable gripping carriage, which carriage clutches one end of a length of material 35 having the first and last buttonhole indicated thereon. The free end of the material is then confined by a suitable presser-foot in such position that the marked point for the first buttonhole is alined under the ma- 40 chine needle. The material is then gripped at the point of the last buttonhole by jaws of the carriage and, for example, should it be desired to divide the distance between the first and last buttonholes to form a com- 45 plete series of five, the carriage is locked in connection with the fifth stop of the series and thereafter the stops are expanded by a suitable mechanism, whereby the material is drawn taut from its confined position un- 50 der the needle, said material, together with the stops, being locked in this confined position. The number of intermediate stops thus corresponds to the number of buttonholes to be worked in the garment between 55 the first and last buttonhole of the series. The gripping carriage is also provided with

an escapement means, whereby after each buttonhole is completed a manual release of the carriage from an opposing stop is effected and the goods is fed forward to align the next point at which a buttonhole is to be formed, the said alinement being effected by engagement of the escapement means with the succeeding stop due to the goods being manually drawn from its free end toward the sewing machine mechanism. The release escapement having returned to its position of rest, will thereby come in contact with the succeeding stop of the series to effect the desired alinement and this 70 operation is repeated so on to complete the series of buttonholes with the exception of the last one, the position of which, as previously stated, is marked upon the goods. The material is thus released from the carriage and the last buttonhole is formed in the ordinary manner due to the fact that it requires no automatic stop mechanism to indicate its position.

With the above objects in view the invention consists in certain peculiarities of construction and combination of parts as hereinafter set forth with reference to the accompanying drawings and subsequently claimed.

In the drawings Figure 1 represents a front elevation of an adjustable stop mechanism embodying the features of my invention, in which exemplification of the invention the same is shown attached to a button-hole stitching machine, with parts broken away and parts in section to more clearly illustrate certain details of construction; Fig. 2, an enlarged detailed cross-section of the gage mechanism, the section being indicated by line 2-2 of Fig. 1, and Fig. 3, a fragmentary elevation of a part of the mechanism looking from the reverse side from that shown in Fig. 1 and showing in particular a gripping carriage and its associated mechanism.

Referring by characters to the drawings, 1 represents a table or other suitable support upon which is mounted the base 2 of a buttonhole stitching machine of any desired type, which machine forms no part of my invention and is therefore diagrammatically shown, the same being provided with the ordinary head 2' and needle bar 2''. The head also carries a clamp or presser foot 3 for confining the goods A to be worked upon. The base-plate 2'' of the

machine is formed with a hub-socket 3 for the reception of one end of a guide-rod 4, the opposite end of which guide-rod is supported in a standard 5 that projects upwardly from the table 1. This standard also supports one end of a carriage-rail 6, the opposite end of which rail abuts the base-plate of the machine and is provided with a depending ear 6' that engages the guide-rod 4, the upper face of said carriage-rail being upon the same plane as the base-plate 2''' of the machine, whereby it forms a continuation of said base-plate for the support of the material A which is to be operated upon.

Slidably mounted upon the guide-rod 4 are a series of eared sleeves 7, the ears of which, for convenience, are provided with indicator marks 2 to 8 inclusive, which marks indicate the maximum number of buttonholes that can be worked in connection with the gage mechanism. It is manifest that this number may be increased or diminished as the case may require.

Each sleeve carries a stop-pin 7', which stop-pins in this instance extend through the sleeve-ears and form pivots for a series of cross-connected links 8, the said series of links being also pivotally connected at their lower ends and at their intersecting points to form an expansible and contractible link movement of the lazy-tong type. The first link 8' of the series is fixedly pivoted to the depending ear 6' of the carriage-rail. One of the intermediate lower pivot-studs 7'' of the link series is provided with an anti-friction roller 8', which roller engages a vertically disposed slot formed in an upturned foot 9' of an adjustable bar 9. This bar is slidably mounted within clips 10, 10', which clips are supported by the table 1 and the foot end of the bar is also supported by an anti-friction roller 9'', which is adapted to ride upon the table. The under face of the bar 9 is provided with a series of rack teeth 9''' which extend through a distance approximately equal to the endwise movement that is imparted to the bar for the purpose of adjustment to be hereinafter described, and the inner end of the thrust bar 9 terminates with an upwardly extended handle for convenience in manipulating the said bar back and forth within its guides. By this connection with the series of hinged links it is obvious that when the bar is moved back or forth the sleeves 7 carrying the stop-pins 7' will be moved equal distance apart throughout the length of the guide-rod within a predetermined range.

After the bar has been shifted to position the stop-pins selected distances apart, the said stop-pins are locked by engagement of the teeth of the bar with the lower face of the clip 10, the said face forming one wall

Thus the stop-pins are provided with means for predeterminedly adjusting the same simultaneously to selected positions and are also provided with means for locking said stop-pins in their adjusted positions.

Mounted upon the rail 6, which rail is preferably T-shaped in cross-section, is a slideable carriage B, the same being provided with downturned feet that overlap the edges of the cross-web of the rail, whereby the carriage is confined. The carriage is provided with a fixed gripping jaw 11, which gripping jaw co-acts with a movable gripping jaw 11', the latter being hinged to an ear 12 that projects upwardly from the base of the carriage. These jaws are spread apart by a coiled spring 13, which coiled spring is interposed between the jaws and encircles a link 14, one end of the same being pivoted to the base of the carriage and the opposite end to the shank of a clamping lever 15. The shank of this clamping lever is also provided with an angled foot 15' so arranged that when the lever is swung to the position shown in Fig. 1, the gripping jaws are closed and when said lever is swung upwardly, the gripping jaws are spread apart by the interposed coiled spring. The base of the carriage is also provided with a pair of laterally extended apertured ears 16 for the reception of a stud 17, which stud carries an escapement mechanism in the form of a lever 18 having a shoe 18' that is normally held in a line of travel to engage the series of stop-pins 7'. The rear end of the shoe 18' is obliquely flared, whereby it will automatically slide over the stop-pins when the carriage is shifted from left to right with relation to the sewing machine, in which direction said carriage is moved by hand when the work is adjusted to the machine. The escapement lever 18 is normally held in a position to abut the stop-pins 7' by a coiled spring 19, one end of which is secured to the stud 17, while the opposite end is secured to one of the stud-supporting ears 16.

From the foregoing description, with particular reference to Fig. 1 of the drawings, it will be understood that, in order to finish a series of buttonholes upon a garment, the stop-pins are first contracted or nested together in a position juxtaposing the sewing machine head. If it is desired, for example, to finish a series of five buttonholes, the forward end of the goods is clamped under the needle bar at a point upon which the first buttonhole is marked or indicated previously. The goods is next clamped to the gripping carriage by manipulating the lever 15, whereby the teeth of the companion jaws 11, 11', are caused to grip the goods at the point indicating the last buttonhole of the series. The carriage is then adjusted upon its rail to a position where the escapement shoe will be engaged by that stop-pin which

is marked 5. The operator then shifts the bar 9 from left to right until the goods A is drawn taut, as shown in Fig. 1, in which position the bar is locked in engagement 5 with the clip 10 and the stop-pins between the sewing machine and stop-pin 5 will be spaced equal distances apart to correctly position the intermediate buttonholes of the series. After the first buttonhole has been 10 completed, the operator manually trips the escapement lever 18 and thereafter grasps the free end of the goods A and draws the latter from right to left, whereby the carriage is caused to travel in the same direction until stopped by the pin marked 4, it being understood that the escapement lever has been released and is positioned to engage said stop. Thus the carriage is moved 15 forward step by step and the series of buttonholes are completed by repeating the operation until the last buttonhole is reached and, as stated, the goods is then released from the carriage, whereby the final buttonhole, which has been previously arbitrarily 20 marked, is completed upon the machine in the usual manner.

I claim:

1. An adjustable gage mechanism comprising a series of shiftable stops, a guide 30 therefor, an expansible and contractible link mechanism connecting the stops, a shiftable carriage arranged to travel in parallel relation to the stops, and means associated with the carriage for releasable engagement with 35 said stops.

2. A gage attachment for sewing machines, a series of stops, a guide therefor, a series of cross-connected links attachable to the stops, means for anchoring the terminal 40 link of the series, means associated with the

links for locking the stops at selective equal spaced distances apart, a track arranged parallel with said stops, a shiftable material-gripping carriage mounted thereon, and an escapement mechanism carried by the 45 carriage for engagement with the aforesaid stops.

3. A sewing machine attachment comprising a rail and a guide-bar extending from one side of said machine, slidable stops 50 mounted upon the guide-bar, a series of cross-connected links attached to the stops, means for securing that end link of the series adjacent to the machine, an adjusting bar secured to one of the links of said series, means for locking said bar in adjusted positions whereby the stops are held at selective equal distances apart, a carriage in 55 slidable union with the rail, an escapement mechanism carried by the carriage for engagement with the stops, and material-gripping means carried by said carriage.

4. A sewing machine attachment comprising a series of link connected stops, a carriage, an escapement mechanism extending 60 from the carriage adapted to engage any one of the stops, means for increasing and decreasing the distance apart of the stops with relation to each other, and means for locking said stops in their shifted positions.

In testimony that I claim the foregoing I have hereunto set my hand at Manitowoc in the county of Manitowoc and State of Wisconsin in the presence of two witnesses. 75

WILLIAM M. BOENNING.
